METHOD OF CHILLING SOLUTIONS

Earl Petty and Karl Finsterbusch, New York,
N. Y., assignors, by mesne assignments, to Sun
Oil Company, Philadelphia, Pa., a corporation
of New Jersey

Application November 6, 1933, Serial No. 696,769

6 Claims. (Cl. 196—18)

Our invention relates to a method of chilling solutions and more particularly to a method of chilling solutions of hydrocarbon oils in liquefied normally gaseous solvents, or mixtures of hydrocarbon oils and liquefied normally gaseous substances.

Currently in the art of dewaxing hydrocarbon oils, it has become the practice to dilute a hydrocarbon oil with a liquefied, normally gaseous solvent and to obtain a chilling effect by evaporating a portion of the solvent to reduce the temperature of the solution. The reduction of temperature effected in this manner is governed by the physical properties of the refrigerant solvent gas and more particularly, its pressure-temperature relations. It will be obvious that the greater the reduction in pressure the greater the expansion of the refrigerant diluent gas, resulting in a corresponding lower temperature.

In dewaxing hydrocarbon oils, for example, it is frequently desired to reach temperatures as low as say minus 50° F. in order to precipitate wax from the hydrocarbon oil. In order to obtain a favorable crystal growth and to obtain the type of crystal which will be readily filterable, it has been found necessary to reduce the viscosity of the oil by forming a solution therewith. In the dewaxing process mentioned above, the liquefied gas is at once a solvent so that it will act as a diluent. To obtain the desired low temperature, it may be necessary in many cases to reduce the pressure to atmospheric and at times to obtain the desired evaporation by means of a partial vacuum or the imposition of sub-atmospheric pressure upon the solution.

Our invention is likewise applicable to treating processes where gasolines, alcohols or naphthas are used and low temperatures are obtained by the evaporation of the normally liquid solvents by the use of sub-atmospheric pressures. In such processes, we may reduce the partial pressure according to our method and thus avoid the use of low sub-atmospheric pressures. For example, in low temperature acid treating, a decrease in temperature may be obtained by reducing the partial pressure in the treating stage by injecting lower boiling substances thereinto.

The difficulty in obtaining a low pressure is increased by the presence of oil in the liquid phase. The heavy oil reduces the partial pressure of the diluent liquefied gas which is usually a hydrocarbon gas of the nature of propane. The disadvantages of vacuum equipment are manifest. Furthermore, from the view of handling the evaporated gas and/or vapors for re-

cycling, it is desirable to obtain the required low temperature for precipitating the wax from the hydrocarbon oil at as high a pressure as possible. A pressure, for example, from 5 pounds gauge to 30 pounds gauge will eliminate the necessity of vacuum pumps and make the handling of gases and/or vapors comparatively easy. It is well known that, in the compression of gases and/or vapors prior to cooling and condensation, the suction pressure materially affects the size of compressors and power required. Both size and power are reduced by increased suction pressure. Thus, it is more economical when recycling to receive the evaporated gas and/or vapors at higher pressure.

In a dewaxing process employing auto refrigeration, that is, cooling a liquid by evaporating a portion of the same, hydrocarbon gases of the nature of propane have been largely employed. In the practice of dewaxing and crystallization with a propane solution, it has been found necessary to chill the solution to at least minus 30° F. or thereabouts, which generally requires a reduction of pressure to atmospheric or lower through successive stages. With the solution in equilibrium at such low temperatures and pressures, difficulties are encountered through boiling and vapor lock in transferring the liquid by pumps or other means. Accordingly, various transfer methods have been used, such as to supercool the solution by applying vacuum to the crystallization vessel and then repressurize the vessel by gas pressure and transfer the liquid to storage, which is carefully insulated. The liquid may then be allowed to come to equilibrium under the effect of its own gas pressure which may be permitted to build up to approximately 5 to 10 lbs. above atmospheric pressure in order that the cool liquid may more readily be pumped to the separating apparatus.

One object of our invention is to provide a method of cooling or sub-cooling solutions or mixtures and more particularly solutions of hydrocarbon oil in a liquefied, normally gaseous solvent in which advantage is taken of Dalton's law of partial pressures in order to obtain the desired evaporation and low temperature without the necessity of resorting to the use of low pressures and/or vacuum.

Another object of our invention is to provide a method of dewaxing hydrocarbon oils by the use of a liquefied, normally gaseous solvent in which evaporation is aided by the use of a gas and the evaporation carried out at successively reduced, equal, or increased pressures or any

combination thereof. We also provide a method in which the evaporation is due entirely to the use of a gas.

Another object of our invention is to provide 5 a method of reducing the amount of diluent that ordinarily would be required to obtain a definite cooling effect by evaporation under any given temperature-pressure conditions by the use of a gas to increase the evaporation of the diluent. For example, assume that it is necessary to evaporate 100 pounds of propane to gain 10 a desired cooling effect, and that 1000 pounds of propane are necessary as a diluent in order to build up sufficient partial pressure to evaporate 15 100 pounds. By use of a gas, thus reducing partial pressure, the amount of diluent required for the evaporation of 100 pounds of propane may be reduced from 1000 pounds to, say 600 pounds.

Another object of our invention, therefore, is 20 to reduce the overall refrigeration load since the reduction in diluent, pointed out above, reduces the total material to be cooled and thus the amount of evaporation necessary for a given cooling effect. This reduction in diluent also reduces 25 the amount of evaporation necessary since there is less total material to be cooled.

Crystal growth is dependent mainly on three factors, namely, time, temperature and concentration. The concentration has a dual aspect— 30 the ratio of the diluent to the oil and the ratio of the diluent to the wax. It has been definitely established that an excess of diluent retards crystal growth. In United States Patent 1,940,014, Earl Petty discloses the method of 35 maintaining the concentration at an advantageous point with respect to promoting crystal growth, by evaporating the diluent at a controlled rate to maintain the oil-solvent ratio, thus preventing an excess of diluent which would 40 redissolve the precipitated wax. In United States Patent 1,940,015, Earl Petty discloses another method of preventing an excess of diluent which would interfere with favorable crystal growth by using an insufficient amount of diluent 45 to obtain the desired low temperature solely by the evaporation of the diluent and obtaining an increment desired low temperature by a preliminary indirect heat exchange step.

Further and other objects of our invention 50 will appear from the following description.

The accompanying drawing, which forms part of the instant specification, is a diagrammatic view of one form of apparatus capable of carrying out the process of our invention.

In general, our invention contemplates the 55 employment of normally gaseous hydrocarbons having from 1 to 5 carbon atoms per molecule and whose molecular weight varies from 16 to 100 and having boiling ranges from minus 265° 60 F. to plus 156° F. In selecting a gaseous mixture for the dual purpose of acting as a solvent diluent refrigerant, we find it advantageous in most cases to utilize the waste or by-product gases or vapors obtained in the processing and 65 refining of hydrocarbon oils, or from natural gases. We may, if desired, employ a substantially pure compound within the boiling range of propane as a diluent, and use lighter gases which are not necessarily solvents as, for example, carbon dioxide, ammonia, or sulphur dioxide, or other light solvent gases, such as methane or ethane for example, as the gas to be used for the reduction of partial pressure. In its last analysis, we inject into the cooling zone 70 in which a pressure reduction will permit the

evaporation of a portion of the liquefied diluent gas, a lighter gas under the same pressure, in order to permit an operation of Dalton's law. The result will be that a greater amount of diluent gas will be evaporated than would otherwise be accomplished unless the pressure was decreased, thus enabling a lower temperature to be reached at the desired pressure. 5

In the normal practice of dewaxing and crystallization by use of propane solutions, as 10 pointed out above, low temperatures are generally required. Naturally, some of the cooling of the wax bearing oil propane solution may be accomplished by heat exchange against the chilled solution from which the wax has been 15 removed. The remainder of the cooling is normally accomplished by autorefrigeration, i. e., evaporation of a portion of the diluent. This refrigeration is generally done in steps in which the pressure is successively reduced to permit 20 evaporation and cooling to the desired temperature. For example, the first evaporator may be held at, say, 15 to 20 pound gauge and the temperature reduced to 0° F. by partial evaporation of propane. The chilled solution would then 25 pass to the second evaporator where the pressure may be reduced to 3 pound gauge with attendant temperature reduction to, say, minus 15° F. through additional evaporation of propane. The solution would then pass from the 30 second unit to the third evaporator where sub-atmospheric pressure would be required to further evaporate propane and reduce the temperature to, say, minus 30° F.

In our method, the solution after heat ex- 35 change is introduced into the first stage evaporator held at, say, 15 to 20 pound gauge. The evaporation of propane, under this pressure, is increased by reduction in partial pressure through the injection of a light gas, such as 40 methane, and the temperature of the solution lowered to, say, minus 10° F. instead of 0° F. as would normally be obtained for the pressure as pointed out above. Subsequently, in the successive evaporators, temperatures of approximately 45 minus 20° F. and minus 30° F. are obtained by introduction of a light gas at correspondingly higher pressures so that the final stage temperature is obtained at atmospheric or higher pressure. Naturally, combinations and sub-com- 50 binations may be developed, such as only introducing a light gas in the final stage instead of all stages.

In our method, all evaporators may be maintained at the same pressure, the liquid being 55 transferred to successive stages by means of pumps or preferably by the gas pressure in the evaporators and obtaining a cooling effect by evaporation of propane through partial pressure reduction by injection of light gas into each 60 stage.

In our method, the pressures of the evaporators may be successively increased by using pumps to transfer the liquid to successive stages and the use of a light gas to reduce partial pressure of propane in each stage and effect evaporation to obtain cooling. 65

It will also be noted that, in our method, cooling may be obtained in solutions that are already at equilibrium under a given pressure, where at 70 these conditions no evaporation or autorefrigeration would take place, since the reduction of partial pressure by the introduction of a light gas will cause evaporation of the diluent propane.

In general, the apparatus and process steps of our methods, outlined above, are similar so that, from the description of one method, others are self evident. More particularly referring to our method wherein the pressure in successive stages is reduced and to the drawing, a hydro-carbon wax bearing oil from tank 1 is pumped by pump 2 through line 3 into line 4 where it is joined by a liquefied, normally gaseous solvent which, for purposes of convenience, we will hereinafter refer to as propane, from tank 5, whence it passes through line 6 to line 4. The propane and oil are thoroughly mixed in an orifice column 7. The proportion of oil and propane may be governed by valves 8 and 9, and may be in a practical example by volume 41% oil and 59% propane, which will be in the neighborhood of 57% oil by weight to 43% propane by weight.

In giving temperatures, pressures, and proportions, as we will in the following description, it is to be borne in mind that these are not to be considered as limitations but are given only to show a practical operation of the process by way of example. The temperature of the mixture may be, for example, about 90° F. upon leaving the orifice column 7. The solution formed in the orifice column passes through line 10 to a cooler 11, which may be cooled by any suitable medium entering from pipe 12 and discharging through pipe 13. Upon leaving the heat exchanger through line 14, the temperature of the solution will be in the nature of 75° F. It then enters a bank of heat exchangers 15 in which the solution is passed in heat exchange with a wax free oil diluent solution, previously separated in the process. The temperature of the wax free oil solution will be about minus 35° F. effecting a considerable reduction in the temperature of the oil propane solution. The wax free oil solution is obtained from tank 16 and is pumped by pump 17 through line 18 to the heat exchanger bank 15, from which it leaves through line 19 to pass to a pressure stabilizer 20 as will be hereinafter more fully described. The solution thus pre-cooled by indirect heat exchange, leaves the exchanger bank 15 through line 21 which terminates in a manifold portion 22 communicating with lines 23 and 24, passing to evaporator crystallizers 25 and 26 respectively. The arrangement is such that evaporator crystallizers 25 and 26 may be operated in parallel, while evaporator crystallizer 27 will be in series with both evaporator crystallizers 25 and 26. In normal operation, however, evaporator crystallizers 25, 26, and 27 will be operated in series. The solution will pass through line 23, valves 28 and 30 being open and valve 29 being closed, into evaporator crystallizer 25. The pressure in evaporator crystallizer 25 is held below the equilibrium pressure of the precooled solution, permitting propane to be evaporated therefrom, through line 31 through separator 32, through line 33, valve 34 being open and valve 36 being closed. Entrained oil and/or liquid propane from the separator will return to the evaporator crystallizer through line 37. The evaporated propane will pass through line 33 into line 38. A light gas is present in main 39. We will describe more fully hereinafter the cycle through which the light gas passes. Light gas from main 39 passes through line 40, valve 41, which is open, into evaporator crystallizer 25.

Inasmuch as the gas from main 39 is considerably lighter, that is of much lower boiling

point than the diluent gas, its presence in the chilling zone within evaporator crystallizer 25 will permit a further evaporation of propane from the solution at a given pressure, than would be obtained if the light gas were not present, due to the operation of Dalton's law of partial pressures. This additional evaporation effect, produced by the light gas, decreases the temperature without a corresponding decrease in pressure as would otherwise be necessary if the action were entirely by autorefrigeration. It is to be understood, however, that the light gas from line 40 may be injected into the oil-propane solution prior to its entrance into the evaporator crystallizer. The injection of light gas, whether directly into the evaporator crystallizer or into the oil-propane solution prior to its reaching the crystallizer, will have the same partial pressure effect in the operation of Dalton's law within the evaporator crystallizer.

In order to control the solution propane from propane storage tank 5 may pass through line 42 which is controlled by valve 43 into the incoming oil propane solution, through line 23. The proportion of diluent gas to the oil is of importance in determining crystal growth and the type of crystal formed so that this can be controlled by the addition of further propane through line 42. When evaporator crystallizers are operated in parallel, it will be understood, of course, that valve 29 will be open so that the solution may pass into evaporator crystallizers 25 and 26 simultaneously.

Continuing the series operation, the chilled solution is withdrawn from the bottom of evaporator crystallizer 25, through line 44 which is controlled by valve 45, passes through valve 46, valve 47, through line 48, into evaporator crystallizer 26, operated at a pressure below the pressure of crystallizer 25, where a further portion of propane is evaporated because of the reduction in operating pressure, through line 49, separator 50, line 51, valve 52, to propane exhaust main 38. The chilled solution is withdrawn from evaporator crystallizer 26 through line 53 which is controlled by valve 54 and passes through valve 55, valve 56, line 57, into evaporator crystallizer 27, it being understood that valves 58 and 59 are closed. When evaporator crystallizers 25 and 26 are operated in parallel, valves 55 and 46 are closed so that the chilled solution from both evaporator crystallizers 25 and 26 will pass through lines 60 and 61 into line 62, thence through line 63, through valve 58 which will be open, into evaporator crystallizer 27.

It is understood, of course, that in evaporator crystallizer 26, further light gas from light gas main 39 may be passed through line 64 which is controlled by valve 65 into evaporator crystallizer 26 in order to reduce the partial pressure of the propane therein, permitting a greater evaporation thereof, thus obtaining a lower temperature under the given operating pressure. In evaporator crystallizer 27, operated at a pressure below the pressure of evaporator crystallizer 26, further propane is evaporated from the solution through line 66, separator 67, line 68, valve 69, to exhaust propane main 38. At the same time, light gas from light gas main 39 will pass through line 70 which is controlled by valve 71, into evaporator crystallizer 27 to permit Dalton's law to operate, obtaining a further reduction in temperature without a corresponding reduction in pressure. Alternately it is to be understood that the light

gas may be injected into the solution before the solution is introduced into each of the evaporator crystallizers 26 and 27. The chilled solution, which by this time is minus 50° F. for example, is withdrawn from the bottom of evaporator crystallizer 27 through line 72 which is controlled by valve 73 and passes through line 74, through valve 75, valves 76 and 77 to filter feed tanks 78 and 79. Filter feed tanks 78 and 79 are equipped with lines 80 and 81, controlled by valves 82 and 83, communicating with low pressure propane main 38 through respective separators 84 and 85. Either feed tank may be employed, or both may be used simultaneously. The solution in filter feed tanks will contain chiefly the oil, while the wax will be present in precipitated form. The oil diluent solution containing the wax in precipitated form is withdrawn from filter feed tanks 78 and 79 through line 86, where it passes through lines 87, 88 and 89 to be pumped by respective pumps 90, 91, 92, through respective filters 93, 94 and 95. The wax diluent mixture leaves the filters 93, 94, and 95 through respective mixers 96, 97, and 98, which serve to keep the wax in liquid slurry form to prevent clogging of line 99 through which the wax diluent mixture passes into petrodatum diluent mixture tank 100. The admixed oil diluent solution filtrate passes through line 101 to the wax free oil solution storage tank 16, whence it passes through line 18, through the heat exchanger bank 15 as hereinbefore described.

Storage tank 16 is provided with a vent pipe 102 and storage tank 100 is provided with a vent pipe 103, allowing such propane as is evaporated by an increase in temperature to escape.

The dewaxed oil solution from line 19 passes into pressure stabilizer 20 in which it is reboiled. The bottom 104 of stabilizer 20 divides the tower 40 into two compartments. The incoming oil diluent solution accumulates upon bottom 104 and is picked up by pump 105 and circulated through reboiler 106 to which any suitable heating medium may be supplied, such as steam or hot oil from 45 any refinery operation, and discharged through line 107 back into the pressure stabilizer 20. The propane is thus driven off and passes into main 108. The wax diluent mixture and/or solution, is withdrawn from tank 100 through line 50 109, which is controlled by valve 110, and passes through a heater 111 which serves to drive the wax into solution and/or render it sufficiently fluid to be handled in a pipe line. Any suitable heating medium may be passed through heater 55 111 through port 112 and out of port 113. The heated wax diluent solution passes through line 114 which is controlled by valve 115, into pressure stabilizer 116, which is equipped with a bottom partition 117 similar to partition 104 of 60 pressure stabilizer 20. Pump 118 circulates the wax diluent solution through reboiler 119, which is supplied by heating medium through port 120, and the heated wax diluent solution is reinjected 65 into the tower through line 121, which is controlled by valve 122. It will be readily appreciated that in respective pressure stabilizers 116 and 20, the diluent gas will be driven off. The gas from pressure stabilizer 116 will pass 70 through line 123, which is controlled by valve 124, into line 108 from which the combined gases pass through line 125, through condenser 126, which is supplied by any suitable cooling medium, through line 127, and leaves condenser 126 through line 128. The cooled gases from condenser 126 pass through line 129, which is con-

trolled by valve 130, into receiver 131. A portion of the liquefied gas from receiver 131 is pumped by pump 132 through line 133, which is controlled by valve 134, through lines 135 and 136 as reflux to the pressure stabilizers 20 and 116. The lighter uncondensed gases pass from the receiver 131 through line 137, which is controlled by valve 138, into the light gas main 39, or into collecting main 38. Propane from the bottom of receiver 131 passes through line 139 which is controlled by valve 140, through line 141, which is controlled by valve 142, through line 143 into condenser 144, which is supplied with cooling medium entering through pipe 145 and leaving through pipe 145a, through line 146, into accumulator tank 147, whence it passes through line 148 to the propane tank 5.

The denuded, dewaxed oil from the upper portion of pressure stabilizer 20 passes through line 150, which is controlled by valve 151, into the lower portion 152 of the pressure stabilizer. This lower portion is virtually a separate chamber. A steam pipe 153 which is controlled by valve 154, discharges steam into chamber 152 in order to strip the last traces of propane from the dewaxed oil. The dewaxed oil is then withdrawn through line 155 which is controlled by valve 156, and pumped by pump 157 through line 158 to storage.

The petrodatum which is sufficiently hot to be handled in a pipe line, is withdrawn from the upper portion of pressure stabilizer 116 through line 160, which is controlled by valve 161, into chamber 162, which is virtually a separate chamber. Steam through pipe 163, which is controlled by valve 164, is injected into chamber 162 to denude the wax from any last traces of propane. The wax is withdrawn from the bottom of chamber 162 through line 165, which is controlled by valve 166 and is pumped by pump 167 through line 168 to petrodatum storage. 40

Line 170 communicates with the upper portion of chamber 152 and is controlled by valve 171. It passes from chamber 152 to line 190. Pipe 180 communicates with chamber 162 and is controlled by valve 181 and passes, together with line 170, to line 190, which communicates with barometric condenser 191. The vacuum will insure the removal of all last traces of gas in both the oil and the wax. The gas is discharged from the barometric condenser 191 through line 192. It will be observed that low pressure propane collecting main 38 communicates with line 200 which passes to suction tank 201, together with the vent line 102 from the wax free oil solution tank 16. Compressor 202 takes suction through line 203 to 55 suction tank 201, compresses the propane and passes it into receiver 204, whence it leaves through line 206 and passes, together with the propane in line 139 through line 141, through condenser 144 to accumulator 147. The uncondensed gases from accumulator 147 will be the light gases which are passed from accumulator 147 through line 207 to the light gas main 39. It will be observed that the accumulator is at once a separator, substantially separating the heavier 60 gases, which will liquefy at comparatively mild temperature and pressure, from the lighter gases so that we can reuse both the propane fractions and the gaseous fractions. Both fractions, of course, are under the same pressure on again entering the system for reuse. If desired, the gaseous fractions may be rejected from the system through line 207a controlled by valve 207b. 70

In event it be desirable to supply further light gases to the system, these may be injected 75

through line 300 which is controlled by valve 301, it being understood of course that the light gases are under pressure and may be obtained from any suitable source such as from previous refinery operations or from natural gas. As pointed out above, ammonia or other non-hydrocarbon gases may be employed if desired.

Inasmuch as the pressure may be sufficiently high and the temperature may be sufficiently low 10 in cooler 144 so that many lighter gases will be liquefied and passed to propane tank 5, we may further our processes in another manner, namely as follows:

A solution of the diluent and the liquefied 15 gases is formed as before. In this connection, it might be well to note that only the lighter gases may be either diluent or non-diluent gas, while the heavier gases are always solvent gases. It is only necessary that sufficient liquid gases be present 20 to act as a diluent solvent. Upon being precooled and arriving at evaporator crystallizer 25, the pressure is reduced as before, but valve 34 is closed and valve 36 is open. The first reduction of pressure will allow the lighter constituents 25 to evaporate. These will pass through line 400 which is controlled by valve 36, into line 64, in which valve 65 is closed, and thus into evaporator crystallizer 26. Similarly, a reduction 30 of pressure in evaporator crystallizer 26 will allow further of the lighter gases to evaporate and valve 52 being closed, and valve 401 being opened, the lighter gases will pass through line 402 into line 70, it being understood that valve 71 is closed, and thence into evaporator crystallizer 35 27, whence all of the light gases will pass through line 68 into exhaust gas main 38. The cycle is repeated as before, the gases being cooled and compressed in order to liquefy them.

In the event that it is not desirable to operate 40 with a closed cycle for the light gas, as previously described, an alternate operation may be used as follows:

No light gas would enter the system through line 300 as valve 301 would be closed and the 45 light gas would pass into the light gas main 39 through line 403, controlled by valve 404. The injection of light gas from main 39 into any or all of crystallizers 25, 26 and 27 may be accomplished through respective lines, as outlined 50 heretofore. The injected gas and evaporated diluent will leave each evaporator crystallizer through respective separators. The cross connecting lines between evaporator crystallizers controlled by valves 36 and 401 would be closed 55 off, as well as valves 34, 52 and 69 in the respective lines leading to discharge main 38. Thus, the gases and vapors, leaving evaporator crystallizer 25, will pass through line 405 which is controlled by valve 406, into discharge main 60 407, and be rejected from the system. Similarly, gases and vapors from evaporator crystallizers 26 and 27 may be directed to line 407. With these connections, it is possible to inject light gas into any one or all evaporator crystallizers and 65 reject or recycle the gases and vapors from any evaporator crystallizer, as desired.

For example, it may be desirous to maintain the evaporated diluent free from light gases for the purpose of recycling the diluent. Thus, 70 vaporized diluent in evaporator crystallizers 25 and 26 may be passed directly to line 38, then through compressor 202, cooler 144 and, after condensation, into propane tank 5. These crystallizers may be operated at super-atmospheric pressure, 75 as well as evaporator crystallizer 27. The final

temperature lowering of the solution may be accomplished in evaporator crystallizer 27 by the use of light gas to effect the greater evaporation of propane. In this case, the gases and vapors from evaporator crystallizer 27 would pass 5 through line 410, controlled by valve 411, into line 407 for rejection. Thus, the vaporized diluent in evaporator crystallizers 25 and 26 may be recycled without contamination of light gases. The loss of diluent through vaporization in evaporator crystallizer 27 may be made up by addition from an outside source to propane tank 5. It is understood that combinations and sub-combinations of this system of recycling and rejecting gases may readily be made.

It may be desirable to operate all the evaporator-crystallizers at super-atmospheric pressure to prevent vapor lock in pumps caused by boiling at reduced pressures and temperatures. The chilled oil-propane solution from line 21 is introduced under pressure through the line 23 and valve 28 into the evaporator-crystallizer 25 where a pressure substantially above atmospheric is maintained by suitable control of the valves 28 and 34 and propane is permitted to evaporate to 20 effect a chilling of the solution. The chilled solution is transferred from this first stage crystallizer to the next stage 26 and into this stage a light gas such as methane, or ethane, is introduced from the line 64 and allowed to vent 25 through the line 51 at a pressure slightly lower than that in the previous evaporator-crystallizer 25. The partial pressure effect of this lighter gas makes it possible to reduce the temperature without again materially reducing the pressure in 30 the evaporator-crystallizer 26. The chilled solution from evaporator-crystallizer 26 may again be transferred to the third evaporator-crystallizer 27 where a pressure slightly lower than that in either of the other stages 25-26 is maintained. 35 A light gas is again introduced through the line 70 and equilibrium conditions established by evaporation with the attendant reduction in temperature. It is to be observed that the light gas may be introduced, if desired, into the solution 40 before the solution enters the evaporator-crystallizers 26 and 27. The oil solution after dewaxing may be relieved of its light gas content by introduction into a flash tower (not shown) 45 in the line 19. The isolated light gases from 50 the top of the tower may be returned to the light gas main 39 while the bottoms of the tower are redirected into the line 19 for passage to still 20.

In operation, it may be seen that there are thus three methods of operation possible with the system.

First, an oil propane solution which has been precooled to a temperature of about 40° F. is pumped through line 21 at a pressure of around 100 lbs. to the evaporator crystallizer 25. The 60 solution under these conditions will be in equilibrium. The solution on being injected into the evaporator crystallizer 25 is reduced in pressure by suitable control of the valve 28 and adjustment of the back pressure by control of the valve 34 in the line 33 until a pressure of around 25 lbs. gauge is arrived at in the evaporator crystallizer 25. Propane will evaporate from the solution with an attendant reduction in temperature until equilibrium conditions are again established. The 70 temperature of the solution will now be around 10° F. The solution may now be transferred under its own pressure through valve 45, line 44, valve 46, valve 47 and line 48 to the evaporator-crystallizer 26 where by suitable manipulation 75

of the valve 47 and valve 52 in line 51 a further reduction in pressure may be achieved and a further reduction in temperature had by propane evaporation. This procedure may be repeated 5 until the desired low temperature is arrived at, at which time, the pressure will have fallen to atmospheric or sub-atmospheric pressure with the attendant difficulty of pumping the chilled solution to the separating units.

10 Secondly, an oil propane solution in line 21 at a pressure of about 100 lbs. gauge and at a temperature of about 40° F. is injected into the evaporator crystallizer 25 where the pressure is reduced to about 25 lbs. gauge by suitable control 15 of the valves 28 and 45. Propane will then evaporate until equilibrium conditions are established and the temperature is reduced to 10° F. as before. A lighter gas is then introduced through the line 41 and due to the partial pressure effect 20 of the light gas, a further reduction in temperature to -5° F. will be effected without further decrease in pressure. The chilled solution will then be transferred under its own pressure as before to the evaporator crystallizer 26. A further reduction in pressure here will permit more 25 propane to evaporate and the temperature will be further reduced. A light gas will again be introduced through line 64 to effect further temperature reduction without a decrease in pressure 30 by operation of Dalton's law. This process may be continued until the desired low temperature is reached.

Thirdly, the oil propane solution at 100 lbs. gauge pressure and a temperature of 40° F. is 35 introduced from line 21 into the evaporator-crystallizer 25 and the pressure reduced to about 30 lbs. gauge by proper manipulation of valves 28 and 34. Propane is permitted to evaporate until equilibrium is restored. The cooled liquid 40 is then transferred to the evaporator-crystallizer 26 where the pressure is only slightly lowered from that in evaporator crystallizer 25 by manipulation of valves 47 and 52. A light gas is then injected through line 64 and a further reduction 45 of temperature effected as a result of the operation of Dalton's law. By introducing the lighter gas at the lower temperature and pressure, a certain percentage of these compounds will be condensed and retained in the chilled solution, 50 whereas if the liquefied hydrocarbon consisting mainly of propane, had contained even considerable quantities of these light materials in the original blend, they would have been flashed off in the first evaporator-crystallizer 25. The solution will be reduced in temperature in the evaporator-crystallizer 26 to about +5° F. It is to 55 be observed that the low temperature secured by the evaporation of propane and a light gas at the lower pressure as in case two is not had in the instant case because of the higher pressure existing in the evaporator crystallizer 26. This disadvantage is offset by the helpful effect 60 of the greater pressure in preventing or minimizing boiling of the solution in its passage through the pumps to the separating units. The process also has the added advantage that less propane is required to effect the desired low temperature than would be required if propane alone were used at the lower pressures.

70 It is believed that the operation will be clear from the above description. It will be seen that we have accomplished the objects of our invention. We are enabled to chill solutions to a lower temperature for a given pressure by the 75 introduction of a light gas into any single one

or a plurality of the evaporation zones. We are enabled to chill solutions or mixtures which are at equilibrium or which are under a pressure which is greater than the equilibrium pressure for a given temperature. Under ordinary conditions or equilibrium no evaporation with attendant chilling would take place. Under our method, we accomplish chilling by the introduction of a light gas. We are enabled to maintain favorable crystallization conditions by avoiding an undesirable excess of diluent which would interfere with favorable crystal growth. At the same time we are enabled to reduce the amount of material to be chilled, thus reducing the refrigeration load and the chilling time interval. 10

15 It will be understood that certain features and sub-combinations are of utility and may be employed without reference to other features and sub-combinations. This is contemplated by and is within the scope of our claims. It is further 20 obvious that various changes may be made in details within the scope of our claims without departing from the spirit of our invention. It is, therefore, to be understood that our invention is not to be limited to the specific details shown 25 and described.

Having thus described our invention, what we claim is:

1. A method of dewaxing hydrocarbon oils including the steps of dissolving a hydrocarbon 30 oil in a liquefied, normally gaseous solvent, cooling the solution by evaporating a portion of the solvent by reducing the pressure on the solution, obtaining a further decrease in temperature of 35 the solution without a further reduction in pressure thereon by introducing a gas of lower boiling point than the solvent gas into the cooling zone to permit an operation of Dalton's law whereby the desired wax precipitating temperature is obtained, permitting wax to precipitate 40 and separating precipitated wax from the solution.

2. A method of dewaxing hydrocarbon oils including the steps of dissolving a hydrocarbon oil in a mixture of liquefied gases of progressively 45 lower boiling points, said mixture containing a component capable of dissolving wax-bearing hydrocarbon oil, reducing the temperature of the solution in a first cooling zone by reducing the pressure on the solution sufficiently to permit 50 evaporation of the lighter gases of the mixture, further cooling the solution in a second cooling zone by evaporating a portion of the heavier gases of the mixture by further reducing the pressure and obtaining a further reduction of 55 temperature of the solution without a further reduction of pressure thereon by introducing the gases evaporated from the first cooling zone into the second cooling zone to permit an operation of Dalton's law whereby the desired wax precipitating temperature is obtained in the solution, permitting wax to precipitate and separating precipitated wax from the solution. 60

3. A method of dewaxing hydrocarbon oils including the steps of dissolving a wax-bearing hydrocarbon oil in a liquefied normally gaseous solvent, cooling the solution in a first cooling zone by reducing the pressure on the solution sufficiently to evaporate a portion of the solvent, obtaining a further decrease in temperature without a further decrease in the pressure on the solution by introducing a gas of lower boiling point than the solvent gas into said cooling zone, passing the cooled solution by means of the gas pressure thereon into a second cooling zone, 70

75

there further reducing the pressure on the solution to obtain another reduction in temperature of the solution and introducing a gas of a lower boiling point than the solvent gas into the second cooling zone to obtain a further decrease in temperature of the solution without a further decrease in pressure thereon and by the process obtaining the desired wax precipitating temperature, permitting wax to precipitate and separating precipitated wax from the solution.

4. A process as in claim 1 wherein the gases freed from the cooling step are compressed and cooled at such temperature and pressure that a portion of the lighter gases are left in the 15 gaseous state while most of the heavier gases are liquefied.

5. A method of dewaxing hydrocarbon oils including the steps of mixing a wax-bearing oil with a liquefied normally gaseous diluent, evaporating a portion of the diluent to chill the solution by reducing the pressure thereon, increasing the extent of the evaporation by introducing a lower boiling gas into the evaporating zone to reduce the partial pressure therein, the process 20 being such that the amount of diluent added in the mixing though maintaining a desirable con-

centration of diluent during the chilling step is less than that amount which would be required to cause sufficient evaporation to give the desired low temperature in the solution if the light gas were not used, whereby the refrigeration load is 5 decreased and excess of diluent during the chilling step is avoided, permitting wax to precipitate and separating precipitated wax from the solution.

6. A method of dewaxing hydrocarbon oils including the steps of mixing a wax-bearing oil with a liquefied normally gaseous diluent, reducing the pressure on the solution thereby evaporating a portion of the diluent by its own partial pressure to chill the solution in a first chilling step, 10 transferring the chilled solution to a second chilling zone, further reducing the pressure on the solution and injecting a lower boiling gas into the second chilling zone thereby evaporating a further portion of the diluent under the partial pressure of the lighter gas in the second chilling step 15 to further chill the solution and precipitate the wax, and separating the precipitated wax from the solution.
